UNITED STATES PATENT OFFICE

127,466

DESIGN FOR A FINGER RING

Abraham Sager, Chicago, Ill.

Application February 28, 1941, Serial No. 99,267

Term of patent 14 years

To all whom it may concern:

Be it known that I, Abraham Sager, a citizen of the United States and resident of Chicago, in the county of Cook and State of Illinois, have invented a new, original, and ornamental Design for a Finger Ring, of which the following is a specification, reference being had to the accompanying drawing, forming a part thereof.

In the drawing, the figure is a perspective view of a finger ring showing my new design.

The undisclosed portion of the outer periphery of the ring is a repetition of the part shown.

I claim:

The ornamental design for a finger ring, as shown and described.

ABRAHAM SAGER.
